Attorney

UNITED STATES PATENT OFFICE.

JAMES M. CODY, OF SEATTLE, WASHINGTON, ASSIGNOR, BY DIRECT AND MESNE ASSIGNMENTS, TO CODY BURGLAR ALARM COMPANY, A CORPORATION OF WASHINGTON.

BURGLAR-ALARM.

1,251,864.

Specification of Letters Patent.

Patented Jan. 1, 1918.

Application filed March 26, 1917. Serial No. 157,380.

To all whom it may concern:

Be it known that I, JAMES MARTIN CODY, a citizen of the United States, and resident of the city of Seattle, county of King, and 5 State of Washington, have invented certain new and useful Improvements in Burglar-Alarms, of which the following is a specification.

My invention relates to an alarm device 10 which is intended for attachment to the handle or knob of a door and which is constructed in such manner that when the knob of the door is turned, as it would be by a person who was trying the door with the intention of entering, the alarm is set off.

The object of my invention is to provide 20 a device of portable character which may be applied to door knobs in general in such way as to produce an alarm when entrance is attempted.

My invention comprises the novel parts and combinations thereof which will be specifically set forth in the claims. In the 25 accompanying drawings I have shown this device in the type of construction which is now most preferred by me.

Figure 1 shows a side view of the device as applied to a door.

Fig. 2 is a similar view showing a slightly 30 different manner of supporting the alarm restraining device.

Fig. 3 is a front view of the same device.

Figs. 4 and 5 are plan views of the restraining devices shown in modifications of structures.

Fig. 6 is a cross section showing more fully the construction of the device whereby the restraining mechanism is mounted upon the key.

40 My invention is based upon the mounting of an alarm device upon the knob of the door and applying thereto a restraining member which is supported from the door independent of the knob, in such manner that 45 when the knob is turned the alarm mechanism is released.

In the drawings 1 represents the door and 2 the alarm mechanism which is mounted upon the door knob. This alarm mechanism may be of any type found suitable. 50 The type most generally used and which I now prefer to employ, is a spring actuated mechanism employing an escapement to vibrate a hammer and a bell placed so that the 55 hammer will contact therewith. As the op-

erating parts of such mechanism is a well known type of structure, I have not shown the same in any detail. In fact, the details of construction of such a mechanism is immaterial. In the drawings 20 represents the 60 bell portion of such a mechanism.

In connection with the escapement of the alarm mechanism, or some other body which vibrates in unison therewith, I employ a bar or wire 21 which, as herein shown, is intended to be connected directly with the escapement and to vibrate in connection therewith. This bar projects beyond the casing of the alarm mechanism. As herein shown and as I prefer to make it, this would extend downwardly therefrom.

For convenience in better securing the restraining mechanism in connection therewith, this rod may be provided with kinks or projections, as 22, of which one or more 75 may be employed, this being intended to engage the restraining member 41 to prevent the same dropping, excepting as it is released by the actuation of the door knob, through the instrumentality of someone on the outside.

The casing 2 is provided with means whereby it may be detachably secured upon a door knob. The means preferred and herein shown, consists of three fingers 3, one 85 adapted to engage the top of the door knob and the other two to engage the sides thereof. These may be of spring character, or shaped to fit closely enough to the door knob so that they may be placed thereon by a 90 downward movement. Any means for securing the device upon the door knob which is convenient and which will adapt itself to different styles of door knobs, may be employed.

95 It is evident that if the bar 21 be engaged and its vibrations prevented, the alarm will not go off, while, if the same is released so that it may vibrate freely, the alarm bell will be rung. I provide a mechanism which is adapted to be secured to, or supported from, the door independently of the door knob and having a member which may be engaged with the bar 21 to prevent its vibration. So long as so engaged the alarm will 100 not ring.

105 One manner of doing this is to secure the restraining member upon a key which is placed in the key hole. The device, as shown in Figs. 1, 5 and 6, is mounted in this 110

manner. This device comprises a base member 4, which is provided with means for securing it upon the key. The means shown for securing this in place consists of a finger 5 43, which engages the opposite side of the head of the key from that of the body 4, and a supplemental mechanism which engages the shank of the key 5. The finger 43 may be of flexible metal, such that it may be bent 10 up into the opening in the handle of the key, to better secure it in place.

As shown in Fig. 5, the member 4 is provided with flanges 52, depending at its sides and adapted to clasp the shank of the key. 15 These may be of spring material, or of soft metal which may be pressed together so as to clamp on to the shank of the key.

Secured to the base member 4, by a pivot 42, is the latch 41 which is provided with a 20 notch 46, in its outer end, which engages with the projecting portion of the vibrating bar, or wire 21. So long as the door knob remains stationary, the latch 41 will hold the vibrating wire 21 and thus prevent the 25 bell from ringing. If, however, the door knob be turned, the wire 21 will lift the latch 41, or displace it in such manner that it will then drop down into position, such as is shown by dotted lines in Figs. 1 and 2.

30 There will then be nothing to prevent the alarm from ringing its bell.

In Fig. 1 I have shown a spring clasp or catch mounted upon the body of the member 4 and adapted to be spread to put it on 35 the shank of a key and then clasped by the action of the spring 44, so as to engage the ends 40 thereof with the shank of the key.

In Figs. 2 and 4 I have shown the member 4 as provided with a split end, 45, preferably having sufficient resiliency or spring

character to enable it to be slipped over the flat head of a bolt operating member, thus forming a support for the restraining device. This restraining device may be mounted in any suitable manner from the door, 45 so long as this is independent of the knob.

What I claim as my invention is:

1. An alarm device provided with means for securing it to a door knob and a restraining mechanism provided with means for securing it upon the door independently of the door knob. 50

2. An alarm device having arms adapted to embrace a door knob and a projecting arm controlling the actuation of the alarm, 55 of a device provided with means for securing it independently of the knob and to engage said alarm controlling arm.

3. A device as described in claim 1 in which the restraining mechanism has two 60 hinged parts one engaging the alarm device and adapted to drop on release of the alarm.

4. A device as described in claim 1 in which the restraining device has two parts hinged together, one part carrying the 65 means for supporting engagement with a key and the other for restraining engagement with the alarm.

5. A burglar alarm comprising a spring 70 actuated alarm bell mechanism, clamping fingers carried thereby and adapted for supporting engagement with a door knob, said alarm mechanism having a projecting bar actuated by the bell actuating mechanism, and a restraining mechanism for said bar 75 provided with means for supporting it independently of the door knob.

Signed at Seattle, Washington, this 20th day of March, 1917.

JAMES M. CODY.
